UNITED STATES PATENT OFFICE

2,571,636

REMOVAL OF METALLIC OBSTRUCTIONS IN
WELL BORINGS BY OXIDATION

Lewis H. Watkins, Caracas, Venezuela

Application October 14, 1947, Serial No. 779,724

5 Claims. (Cl. 166—1)

1

This invention relates to well drilling or oil well producing, and more particularly to an improved apparatus for removing metallic obstructions, such as lost tools, drill-stem sections, tubing, fishing tools, packers, plugs, casing, etc., from well borings of any depth, especially deep borings such as those drilled for oil, by oxidation.

In drilling wells, such as deep oil wells, it frequently happens that a drilling bit, or other tool becomes detached from the drill stem to remain as an obstruction within the well bore. The drill stem itself may twist off and a section thus becomes lodged in the hole, defying mechanical means of being dislodged and brought to the surface.

Present-day fishing tools may themselves be lost in the hole after engaging the "fish" but unable to dislodge it. Joints or sections of casing often collapse, are torn from the main string, and become obstructions to further progress.

When any of these accidents occur, it becomes impossible to proceed with the normal drilling operation until the obstruction in question has been removed, or in some manner displaced from the bore of the well.

In conventional drilling practice, failure to remove (or by-pass) the obstruction may result in the abandonment of the well. And as this may happen at a depth of several thousand feet below the surface of the ground, such an abandonment entails a substantial financial loss and large waste of time, labor, etc. Loss of production alone may amount to huge sums.

The fact that the obstructing body in the well bore may be at great depth increases the difficulty and time necessary to engage the object with a mechanical fishing tool, or otherwise dislodging or removing it.

It is among the objects of the present invention to provide suitable apparatus for removing the obstructing metallic body, or bodies from well borings by burning such bodies, that is, consuming the body by oxidation to substantially complete destruction, and to fuse or vaporize the obstruction inside the well bore, whether cased or open, and while submerged in fluid mud or water at the bottom of the bore, which method is effective to quickly and completely destroy any kind of metallic obstruction in a well bore, is relatively inexpensive when compared with the present practice of mechanically fishing for such an obstruction, and which can be performed by use of conventional well-drilling equipment and a simplified unit of special apparatus which may be lowered through the well bore to the location of the obstruction.

2

A further object resides in the provision of an improved apparatus which employs the method for destructively removing a metal body obstructing a well bore which comprises raising the temperature of such a body to the oxygen ignition temperature of the metal of which it is formed and subjecting the body so heated to an oxidizing atmosphere until destruction thereof by burning is substantially completed.

10 Other objects and advantages will become apparent from a consideration of the following description in conjunction with the accompanying drawings, wherein:

Figure 1 is a diagrammatic longitudinal cross-section of a well bore, such as the bore of an oil well, showing a metallic obstructing body in the bore and apparatus illustrative of the invention positioned to remove the obstructing body from the well bore;

20 Figure 2 is a longitudinal cross-section on a somewhat enlarged scale of the fragmentary upper-end portion of the apparatus illustrated in Figure 1;

Figure 3 is a plan view of the lower end of the apparatus;

25 Figure 4 is a diagrammatic view similar to Figure 1 showing in longitudinal elevation a modified form of apparatus especially equipped for operation while submerged in fluid to a great depth, portions being broken away to better illustrate the construction thereof;

Figure 5 is a longitudinal cross-section of the fragmentary upper end portion of the apparatus shown in Figure 4;

30 Figure 6 is a bottom plan view of the apparatus shown in Figure 4; and

Figure 7 is a fragmentary longitudinal cross-section similar to Figure 5 showing a still further modified form of apparatus.

With continued reference to the drawings, 40 there is diagrammatically illustrated a vertical well bore, generally indicated at 10, into which is inserted a conventional tubular casing 11. The drawings illustrate a conventional boring tool or bit 12 as having become detached from the tool stem and lost in the bottom of the bore. It is to be understood, however, that such a boring tool in the bottom of the well bore represents only one type of obstruction. Various other mechanical devices may be lost in the well bore and may become lodged at various positions longitudinally of the bore. For example, the tool stem itself may break and assume a twisted or inclined position in the bore from which it is impossible to dislodge it by mechanical means. An entirely 45 different type of boring bit may be lost and

various other pieces of drilling or pumping equipment, any one of which will constitute an obstruction which will preclude further drilling of the well bore until removed or dislodged from the bore.

In carrying out the present method, there is provided a generally cylindrical container 13 which is filled with a quantity of material which, when ignited, burns at an excessively high temperature and contains sufficient oxygen to support combustion in the absence of atmospheric oxygen. Such material may comprise a mixture of finely divided aluminum and an oxide of a metal of lower chemical activity than aluminum, such as iron oxide. These ingredients may be mixed in various proportions and may be combined with other components as may be found necessary or desirable. The principal requirement of the combustible mixture 14 in the container 13 is that it burns at a temperature sufficient to heat the obstructing body 12 to a temperature at which the metal of the body will ignite and burn in an oxidizing atmosphere.

A conventional time fuse 15 is secured in the bottom wall of container 13 and may be set to ignite the mixture 14 in the container at any desired time interval after the setting of the fuse. This fuse may be of any desired construction and arrangement to perform the indicated function, but a conventional artillery fuse has been found to give entirely satisfactory results.

The container 13, together with the fuse 15, and the mixture 14 filling the container constitute an incendiary bomb which, when ignited and brought substantially into contact with the obstructing body 12, will heat the body 12 to the desired high temperature and cause the body to burn or decompose.

In the arrangement illustrated, a second container 16 is disposed immediately above the container 13 and preferably has its bottom end secured to the upper end of the lower container 13. The container 16 contains a suitable flux mixture 17 which may be a mixture of limestone and iron filings or any material or combination of materials which will promote the burning of the metallic body 12 once burning thereof has been started by the action of the mixture 14 in container 13.

A third cylindrical container 18 is disposed immediately above the container 16 and preferably has its bottom end secured to the top end of the intermediate container 16.

While the flux container 16 has been illustrated as disposed in operative position between the incendiary bomb and the container 18, it may be disposed in some other position, if desired, or may be entirely omitted in any particular instance in which its presence is not required.

The container 18, as illustrated, is hollow and adapted to contain oxygen under pressure. This container may be made as long as desired to contain a sufficient quantity of oxygen for the complete combustion of an obstructing body, the total length of the three containers 13, 16 and 18 being limited only by the capacity of the conventional well derrick by means of which the apparatus is lowered in the well bore.

A conventional gas valve 19 is provided at the top of the container 18 and has a threaded fitting 20 to which a tube may be connected for introducing oxygen under pressure into the container. The valve is controlled by a conventional hand-wheel or similar device 21, and is provided with a pressure gauge 22 by means of which the pressure

of the gas in the container may be observed at any time.

An internally screw-threaded cylindrical collar 23 is threaded onto the upper end of the container 18 and a dome-shaped cap or plug 24 is threaded into the projecting upper end of the collar. This plug has cut-away portions 25 providing windows through which the valve 19 may be operated and through which the gauge 22 may be observed, and has secured to its upper or dome end an extension 26 having its upper end formed to provide an externally screw-threaded conical pin 27, or tool-joint, to which is secured the lower end of a cylindrical cable box 28 which receives the lower end of cable 29 therein for suspending the entire apparatus from the cable. The cable may be secured in the cable box by conventional means, such as by embedding the end of the cable within the box in babbitt or similar metal.

A plurality of tubular conduits 30 extend downwardly from the lower end of the oxygen container 18 and through the bottom wall of the bomb 13 with their lower ends positioned around the fuse 15, as is clearly illustrated in Figure 3. These tubular conduits have their lower ends plugged or sealed by a suitable fusible material so that oxygen cannot escape through them until the plugs are fused after ignition of the bomb 13.

In carrying out the improved method, after a metal tool or part, such as the bit 12, has been lost in the well bore, the remaining part of the tool stem, and other structure still attached to the hoisting mechanism of the derrick is removed from the bore.

The apparatus, including the bomb 13, the oxygen tank 18, and, if desired, the flux container 16, is then secured to the end of a hoisting cable and suspended above the top of the well as a unit, the oxygen container being filled with oxygen to the desired pressure. The fuse 15 is then set to ignite the material 14 in the bomb after a desired time interval sufficient for lowering the apparatus to the point of obstruction in the well bore. The apparatus is then lowered in the well bore until the lower end of the bomb is in contact with or is at the location of the obstruction and is held in this position until the fuse acts to ignite the combustible material in the bomb. Upon ignition, this material burns at an exceedingly high temperature, temperatures of from 3800 to 4200 degrees centigrade being usual for such materials. This exceedingly high temperature heats the obstructing body to a temperature at which the metal of the body will burn in oxidizing atmosphere, and may even reduce the body to a molten condition. The quantity of material used will be dependent upon the amount necessary to heat the body to the desired temperature, but it is not necessary to attempt to destroy the obstructing body by merely the application thereto of the heat generated by the combustible material. The burning of the material in the bomb will fuse the plugs or seals in the lower ends of the oxygen conduits 30 and immediately oxygen, under pressure, from the tank 18 will flow through these tubes and envelope the obstructing body, impinging upon it and producing an oxidizing atmosphere around it, so that the body begins to actively burn in the oxidized atmosphere. The containers 15, 16 and 18 have a diameter less than the diameter of the well bore, such as to provide an annular space 31 through which the products

of combustion of the obstructing body can pass.

upwardly through the bore and the body will thus be removed mainly in the form of gaseous products of combustion, any cinder or ash residue being easily displaced by the drilling tools when reinserted in the bore.

A deep oil well bore normally contains a column of fluid mud 31 in the lower portion thereof and it is thus necessary that the destructive action of the obstruction-destroying apparatus take place while the apparatus is submerged in this column of mud. This is accomplished by supplying all of the necessary oxygen to complete the destruction of the obstructing body to the body, so that the burning of the body will be carried out even though the location is submerged.

If the weight per volume of the apparatus is insufficient to cause it to sink through the mud with sufficient rapidity, additional weight can be added by securing one or more lengths 32 of drill stem between the plug 24 and the cable 29. As this drill stem is quite heavy, a few lengths or sections will be sufficient to force the apparatus down through the column of mud at the desired rate.

As the pressure of the fluid column at or near the bottom of a deep well is very high, several thousand pounds to the square inch being not uncommon, it is necessary when operating under such conditions to force the oxygen from the oxygen container against this outside pressure. While this might be accomplished in several ways, as by using an explosive charge in the oxygen container or a differential area piston subjected to the external pressure, simplified and effective means for accomplishing this result are illustrated in Figures 4, 5, 6 and 7.

In the arrangement shown in Figures 4, 5 and 6, the domed plug 24 of Figure 1 is omitted and an outer end plug 33 is threaded into the outer end of collar 23. This plug has a central aperture which receives a piston rod 34. The aperture is surrounded by an internally screw-threaded boss 35 into which is threaded a packing gland 36 which compresses packing 37 around piston rod 34.

An inner end plug 38 is threaded into the collar into contact with the adjacent end of oxygen container 18 and is also provided with a central aperture receiving the piston rod 34. The joint between inner plug 38 and the piston rod may also be packed, if desired.

A piston 39 is disposed in the upper end of container 18 and provided with a central aperture receiving a reduced end portion 40 of piston rod 34. Piston rod end portion 40 is externally screw threaded to receive a nut 41 and lock nut 42 which clamp the piston between the nut and annular shoulder 43 at the inner end of reduced extension 40 so that the piston is immovable relative to the piston rod. A packing 44 seated in an annular groove in the piston provides a fluid or gas seal between the piston and container 18.

Since the hollow plug 24 is eliminated and the upper end of container 18 is not available for mounting the valve 19 and pressure gauge 22, the valve may be connected to the lower end of one of the tubes 30 and the pressure gauge to another of these tubes, as shown in Figure 4. Although when in this position, the valve and gauge will be destroyed upon ignition of bomb 13, this is of no important consequence and does not affect the operation of the apparatus.

In order to force piston 39 down in container 18 after ignition of the bomb and thereby expel

the oxygen from the container 18 through tubes 30 a suitable weight is applied to the upper end of piston rod 34. This weight may be applied by attaching the lower end of a tool stem section 27 to the upper end of the piston rod and permitting the weight of the section to bear on the rod. Each such section is very heavy and a number of sections may be applied in end-to-end relationship as may be necessary to develop the necessary force on the piston to drive the oxygen out of the oxygen container, or by impact of the assembly.

Figure 7 illustrates an arrangement whereby a sufficient oxygen expelling force may be applied to the piston with the use of less weight than in the arrangement described above. By the use of the modified arrangement of Figure 7 the desired result may be accomplished with the use of only one or two drill stem sections regardless of the height of the fluid column in the well and the fluid pressure at the location of the obstruction.

In this arrangement, a conventional shear relief valve 45 having a shear pin 46 of predetermined resistance to shear is extended through end plugs 33 and 38 from the exterior of the container above outer plug 33 to the space between inner plug 38 and piston 39. When the container reaches a depth in the well bore at which the fluid pressure reaches the value for which the shear relief valve is set, the valve opens and admits the external fluid pressure to the top of piston 34 to assist the tool stem sections attached to the piston rod in forcing the piston down in the oxygen container to expel the oxygen therefrom.

A second shear relief valve is shown also extending through plugs 33 and 38. This is merely a duplicate valve to insure operation of the device in the event of the failure of one of the shear relief valves to open.

It is probable that most of the containers 13 and 16 will be consumed during the burning of the body 12. Any unburned portion of the apparatus, however, will adhere to the cable 29 and may be withdrawn from the well bore when the burning operation is completed.

If it is found that a single unit of apparatus is not sufficient to completely destroy the obstructing body, as might be the case if a considerable length of tool stem were lost in the bore, the obstruction-destroying operation can be repeated until the obstructing body is entirely destroyed and no longer causes any obstruction to continue drilling of the bore.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. An apparatus for destructively removing an obstructing metallic body from a well bore comprising a container movable through said bore and containing a body of incendiary composition which, when ignited, is capable of generating heat at a temperature destructive to said obstructing body, means carried by the container for igniting the composition, an oxygen container

mounted on said first container and disposed thereabove; tubes depending from the oxygen container and disposed in communication therewith, said tubes extending through the first container and terminating therebelow, and fusible closures in the lower terminals of the tubes, said closures being fused by the heat of initial ignition of the incendiary composition to open said tubes and permit oxygen escaping from the container to envelope the obstructing body and produce an oxidizing atmosphere around it.

2. An apparatus for destructively removing an obstructing metallic body from a well bore comprising a container movable through said bore and containing a body of incendiary composition capable, when ignited, of generating heat at a temperature destructive to said obstructing body, a settable igniter carried by said container in operative association with said body of incendiary composition for igniting the latter, an oxygen container secured to said first container and positioned thereabove when said apparatus is in a well bore, tubes extending from said oxygen container in communication therewith and extending through the first container, said tubes having free terminals positioned below the first container, fusible closures in the free terminals of said tubes, said closures being fused by heat of the initial ignition of the incendiary composition to open said tubes and permit oxygen escaping from the container to envelope the obstructing body and produce an oxidizing atmosphere around it.

3. An apparatus for destructively removing an obstructing metallic body from a well bore comprising a container movable through said bore and containing a body of incendiary composition capable, when ignited, of generating heat at a temperature destructive to said obstructing body, a settable igniter carried by said container in operative association with said body of incendiary composition for igniting the latter, an oxygen container secured to said first container and positioned thereabove when said apparatus is in a well bore, tubes extending from said oxygen container in communication therewith and extending through the first container, said tubes having free terminals positioned below the first container, fusible closures in the free terminals of said tubes, said closures being fused by the heat of initial ignition of the incendiary composition to open said tubes and permit oxygen escaping from the container to envelope the obstructing body and produce an oxidizing atmosphere around it, and means in said oxygen container for forcing oxygen therefrom through the tubes against the pressure of a column of fluid in said well bore, said means comprising a piston slidably mounted in the upper end of said oxygen container, a piston rod connected to the piston, a top end plate for said oxygen container formed for sealing engagement around the piston rod which passes slidably therethrough, and means extending to the top of the well bore for actuating said piston rod to effect a downstroke of the piston.

4. An apparatus for destructively removing an obstructing metallic body from a well bore comprising a container movable through said bore and containing a body of incendiary composition capable, when ignited, of generating heat at a temperature destructive to said obstructing body, a settable igniter carried by said container in operative association with said body of incendiary

composition for igniting the latter, an oxygen container secured to said first container and positioned thereabove when said apparatus is in a well bore, tubes extending from said oxygen container in communication therewith and extending through the first container, said tubes having free terminals positioned below the first container, fusible closures in the free terminals of said tubes, said closures being fused by the heat of initial ignition of the incendiary composition to open the tubes and permit oxygen escaping from the container to envelope the obstructing body and produce an oxidizing atmosphere around it, means in said oxygen container for forcing oxygen therefrom through the tubes against the pressure of a column of fluid in said well bore, said means comprising a piston slidably mounted in the upper end of said oxygen container, a piston rod connected to said piston, a top end plate for said oxygen container formed for sealing engagement around the piston rod which slidably passes therethrough, means extending to the top of the well bore for actuating said piston rod to effect a downstroke of the piston, and a shear relief valve extending through said top plate operative to admit fluid pressure from the well bore into the oxygen container to act on the top surface of said piston when fluid pressure in said bore reaches a predetermined value to assist said actuating means in forcing said piston downwardly in the oxygen container.

5. In an apparatus for destructively removing an obstructing metallic body from a well bore, a container movable through said bore and containing a body of incendiary composition capable, when ignited, of generating heat at a temperature destructive to said obstructing body, initial igniting means carried by said container, an oxygen container overlying the first container, tubes carried by the oxygen container in communication therewith and extending, when the apparatus is operatively disposed in a well bore, to a point below the first container and fusible closures in said lower ends of the tubes, said closures being fused by the heat of initial ignition of the incendiary composition to open the tubes and permit oxygen escaping from the container to engulf the obstructing body and produce an oxidizing atmosphere around it, a piston slidably mounted in the oxygen container for forcing the oxygen through the tubes, means extending to the top of the well bore for actuating said piston and valve means carried by said container operative to admit fluid pressure from the well bore into the oxygen container to act on the top surface of said piston when fluid pressure in said bore reaches a predetermined value to assist said actuating means in forcing the piston downwardly in the oxygen container.
